UNITED STATES PATENT OFFICE.

JACOB THOMAS MOYER, OF MILFORD SQUARE, PENNSYLVANIA, ASSIGNOR OF ONE-HALF
TO CHARLES J. BARR, OF MILFORD SQUARE, PENNSYLVANIA.

RULE-CLAMP.

No. 916,473.

Specification of Letters Patent. Patented March 30, 1909.

Application filed May 18, 1906. Serial No. 317,556.

To all whom it may concern:

Be it known that I, JACOB THOMAS MOYER, a citizen of the United States, and resident of Milford Square, county of Bucks, and 5 State of Pennsylvania, have invented certain new and useful Improvements in Rule-Clamps, of which the following is a specification, reference being had to the accompanying drawing, forming a part thereof, in 10 which similar characters of reference indicate corresponding parts.

This invention which is an improvement on my Patent No. 814,722, of March 13, 1906, relates to clamps for holding and 15 retaining objects of elongated rectangular contour, the special application of the device being the retention of a folded two-foot, or other length, measuring rule, in such a manner that a carpenter or other 20 artisan may constantly have it in handy position ready for use.

The object of the invention is to provide a continuously operative device of this character which is adapted to clamp the rule in 25 such a manner as not to scratch or mar the faces thereof which contain the scale, and which is inexpensive, durable and simple in construction.

In practice it has been found that when 30 my rule holding device, for which said patent was granted, has been subjected to long or hard usage, the seam at which the walls are joined is insufficient to hold the walls in proper working position and that 35 then the rule often falls out to the great annoyance of the operator. It is to obviate this difficulty that my present invention has been devised.

The invention will be hereinafter fully 40 described and specifically set forth in the annexed claim.

In the accompanying drawings forming part of this specification Figure 1, is a side view of my improved device, showing the 45 device in position to be attached to a pocket; Fig. 2, a similar view showing the device clamped to a pocket; Fig. 3, a rear view thereof; Fig. 4, a sectional plan view taken on the line $x-x$, of Fig. 3, Fig. 5, is a plan 50 view of the device, in blank, before it is formed into shape and, Fig. 6 is a front view of the completed device.

The device embodies a rectangular box A, formed by the parts 1, 2, 3, 4 and 5, of

the blank B, which is composed of resilient 55 sheet metal, the free end or edge part 6, of the part 1, of the front wall in conjunction with the edge part 7, of the front wall section 5, forming a joint 8, where the said edges overlapping each other, and bearing one on 60 the other, add strength and rigidity to the structure, and prevent the parting of the said edges one from the other.

Extended upwardly from the front wall is a slightly curved flange 9, and extended 65 upwardly and then downwardly from the rear wall 3, is a tongue 10, which is provided with a slot 11.

Depending from the lower end of the front wall is a tongue 12, and located opposite thereto and extended from the lower end of the rear wall 3, is a similar tongue 13, these 70 said tongues are perfectly flat and smooth for contact with the marked faces of the rule without liability of marring the same, all 75 clamping action being exerted by the clamping jaws which bear on the reinforced edges of the rule, as will be hereinafter fully described. Extended from the lower end of the side wall 2, is an inwardly bowed clamping jaw 14, and a similar jaw 15, is extended from the opposite wall 4, these are adapted 80 for frictional contact with the reinforced edges of the rule, for clamping and retaining the same within the device. The side walls 85 are also provided with outwardly curved flanges 16 and 17.

It will be noted that the flange 9, in conjunction with the connecting loop of the tongue 10, and the side flanges 16 and 17, 90 forms a mouth or guideway to facilitate introduction of an object into the device from the top, whereby such objects may readily be introduced into the box, and thence forced between the jaws 14 and 15 without liability 95 of scratching or marring the faces of the rule during the operation of inserting the same.

Located on the inner surface of the tongue 10, is a flat bar C, having a lever c, extended therefrom and through the slot 11. This 100 bar C, has a sharp-toothed inner edge d, and its outer edge parts e, form shoulders to bear against the inner surface of the tongue 10, so that when swinging the bar the said tongue may be forced outwardly, to admit of a piece 105 of fabric as D, being clamped tightly against the wall 3, as shown in Fig. 2, of the drawings.

In the operation and use of the invention the bar C, is placed in position shown in Fig. 1, when the device is to be clamped over the edge of the elongated pocket which artisans generally have in the clothing for carrying a rule, the tongue 10, on the outside, so that the rule may be retained by the device, within the pocket, to prevent the same from falling out when the artisan stoops over, then 10 the lever C, is moved into position shown by Fig. 2, which drives the toothed edge d, of the bar C, against the fabric and thus secures the device. But the tongue 10, may also be placed back of the upper edge part of any 15 pocket, a loop or a belt forming part of the garments of a wearer, whereby said part is clamped between the tongue 10, and the rear wall 3, of the box, and the device is retained in position and prevented from accidental 20 displacement by means of the bar C, which presses into the fabric; and withal the device can be readily removed by swinging the lever C, back into position shown by Fig. 1, of the drawings. Having placed the device in suitable 25 position, a rule can be inserted or removed either from the top or bottom, the bowed parts of the sprung jaws 14 and 15 securely clamping and retaining it in place.

Having thus described my invention, what

I claim as new and desire to secure by Letters Patent, is:—

A clamp for retaining elongated objects, comprising a rectangular box made of resilient material, having a seam in its front wall where the adjacent edges overlap and bear on each other, having an outwardly curved flange extended from the upper end of its front wall, and similar flanges extended from its side walls, and an inwardly bowed clamping-jaw extended from the lower end of each of its side walls, and a tongue having a slot and extended upwardly and then downwardly from the upper end of its rear wall, and fastening means comprising a bar having a swinging lever working pivotally in said slot and in connection with said tongue adapted to secure detachably said clamp to a garment, substantially as shown and described.

In testimony that I claim the foregoing as my invention, I have signed my name in presence of two witnesses, this ninth day of May, 1906.

JACOB THOMAS MOYER.
